(57) **CLAIM**

What is claimed is the ornamental design for a bottle, as shown and described.

DESCRIPTION

FIG. 1 is a front view of the first variant of the bottle;

FIG. 2 is a right-hand side view thereof;

FIG. 3 is a left-hand side view thereof;

FIG. 4 is a rear view thereof;

FIG. 5 is a front and right-hand side perspective view thereof;

FIG. 6 is a top view thereof; and,

FIG. 7 is a bottom view thereof.

The broken lines depict portions of the bottle that form no part of the claimed design.
